UNITED STATES PATENT OFFICE.

GEORGE P. KINGSBURY, OF BROOKLYN, NEW YORK, ASSIGNEE TO MERGENTHALER LINOTYPE COMPANY, A CORPORATION OF NEW YORK.

TYPOGRAPHICAL CASTING-MACHINE.

1,116,441.

Specification of Letters Patent. Patented Nov. 10, 1914.

Application filed April 7, 1914. Serial No. 630,311.

To all whom it may concern:

Be it known that I, GEORGE P. KINGSBURY, a citizen of the United States, residing at Brooklyn, in the county of Kings and State 5 of New York, have invented certain new and useful Improvements in Typographical Casting-Machines, of which the following is a specification, reference being had therein to the accompanying drawing.

10 My invention relates to typographical casting machines, such for instance as presented in U. S. Letters Patent No. 436,532, to O. Mergenthaler, wherein slugs or linotypes are cast in a slotted mold mounted in 15 a rotatable wheel, whereby the mold is presented first in operative relation to the composed line of matrices, which is confined at its ends between two jaws, and thereafter in relation to the ejecting mechanism.

20 It is the common practice to provide the wheel or disk with two or more molds differing in size, so that by rotating it and changing its relation to its driving mechanism, one mold or another may be brought 25 into action at will. As the length of the mold slot is thus frequently changed, it is necessary that the matrix-confining jaws be adjustable to correspond therewith, and so that matrix lines of one length or another 30 may be used as desired. It is the purpose of my present improvements to provide mechanism whereby the line-confining devices or jaws will be automatically adjusted to correspond with any selected mold which 35 is brought into action. The nature, construction, and operation of my invention will be described in the specification and finally pointed out in the claims.

In the accompanying drawings, I have 40 shown my improvements only in preferred form and by way of example, and as applied to the specific style of mechanism referred to, but obviously many changes and variations may be made therein, and in its 45 mode of adaptation, which will still be comprised within its spirit. Also, it may be applied to other forms of typographical machines, such as cast type or dies or matrices, instead of slugs or linotypes. Generally 50 speaking, I desire it to be understood that I do not limit myself to any specific form or embodiment, except in so far as such limitations are specified in the claims.

Referring to the drawings: Figure 1 is a 55 front elevation, partly broken away, of a

portion of a linotype machine embodying my invention; Fig. 2 is a side view thereof, partly broken away; Fig. 3 is a sectional detail on the line 3—3 of Fig. 1; Fig. 4 is a view similar to Fig. 2, but showing the parts 50 in different position; Fig. 5 is an end view of the adjustable jaw; Fig. 6 is a sectional detail on the line 6—6 of Fig. 5; Fig. 7 is an enlarged front view of the movable jaw, its adjusting connections, etc.; and Fig. 8 is 55 an enlarged detail.

The vise frame A, mold disk or carrier B, the several molds C carried thereby, the confining jaws D and D¹, the justification slide E, and the devices F to control the jaw D 70 at the time of justification, are substantially the same as in the Mergenthaler patent referred to, or in the commercial linotype machine.

The several molds C carried by the disk B are of different size and form, the length of the slot being ordinarily determined by that of the detachable liner C¹. In ordinary operation, the disk B rotates in such manner as to move the active mold from the 75 casting mechanism to the ejecting means, and then again to the casting position. In order to substitute another mold therefor, the disk B is adjusted relatively to its actuating means, this being preferably accomplished by the lateral movement of the driving pinion G, so as to free it from the pin G² connected to the rotating mechanism G², and the subsequent manual rotation of the disk by the pinion, after which the latter is restored to operative position. This 80 construction and mode of operation is substantially similar to that disclosed in U. S. Letters Patent to W. H. Randall, No. 758,102.

When a new mold, having a different 95 length of slot, is brought into operation, it is desirable that a corresponding change in the distance between the jaws D and D¹ be effected. To permit this adjustment, the 100 jaw D is connected to its normal actuating devices by the rod H, circumferentially grooved or ribbed as at H¹⁰, which passes through and is detachably connected to the 105 jaw, as best shown in Figs. 5 and 6. The grooves or ribs H¹⁰ are flattened or cut away at their opposite sides, so that in one position they engage correspondingly located notches D¹ in the jaw D, but when turned 110 through an angle of 90° are disengaged.

therefrom, and thus permit the relative longitudinal adjustment of the parts, in a manner substantially similar to that presented in U. S. Letters Patent to M. W. Morehouse, No. 826,593.

In order to disengage the rod H and jaw D automatically, so as to permit the adjustment of the latter at the time a new mold is to be brought into position, I mount an arm H' upon the rod H, the end of the arm being located at the side of the pinion G, and between it and a projecting flange or finger G⁴ thereon, so that when the pinion is moved laterally to adjust the disk B (see Fig. 4), the rod will be disengaged from the jaw, and when the pinion is restored to normal position (see Fig. 2), the rod and jaw will be again engaged. In other words, the preparatory movement of the pinion G, necessary to adjust the mold disk B, unlocks the jaw D and leaves it in condition to be adjusted in the manner subsequently described.

The immediate means for adjusting the jaw comprise an arm J (see particularly Fig. 7) connected thereto at one end, and at its other end mounted on the rock shaft K, and the spring J¹ connected to the arm and tending normally to shift the jaw to its extreme outermost position. A sleeve K¹ (see particularly Fig. 3) is also mounted upon the rock shaft K, and connected thereto by a spline, so as rotate therewith but be capable of a limited longitudinal movement thereon. The sleeve is engaged by the pivoted shift lever K², the other end of which is located between the side of the pinion G and the projecting flange or finger G⁴, so that when the pinion G is in its normal engaged position (Fig. 2), the sleeve K¹ is at the extreme right, but when the pinion G is disengaged (Fig. 4), the sleeve is at the extreme left. The latter position of the sleeve brings its depending arm L into proximity to the side of the mold disk B and in condition to be acted upon by the pin or abutment M thereon, when the disk is rotated to bring another mold into action.

The pin M is carried by a plate M¹ formed with a plurality of holes M², suitably located and marked to correspond to the several lengths of molds with which the machine is equipped. If a mold be replaced by another, or if its length be altered by the substitution of a different liner C¹, the pin M is inserted in the corresponding hole M², so that when that mold is brought into action by the relative rotation of the disk, the pin acts upon the arm L, and through the sleeve K, rock shaft K, and arm J thereon, the jaw D is adjusted to correspond. It will be understood that there will be a pin M and plate M¹ for each mold C, although not necessarily located in immediate proximity thereto.

For instance, in Fig. 7, the jaw is shown as

adjusted in relation to the upper mold by the pin M in the plate M¹ at the lower left hand corner.

The holes M² in the plate M¹ (see Fig. 7) are so disposed as to correspond to a unit adjustment of the length of the mold slot, the unit being preferably an em. In order to permit the adjustment of the jaw to correspond to lengths of slot involving a fraction of a unit, such as an en or a half-em, I preferably cut away a portion of the head of the pin M (see Fig. 8), so that either its full contour or the cut-away portion may be brought into active position. In this manner I readily secure the fractional adjustment desired, and obviate the multiplication of the holes M², which would otherwise be necessary.

The general operation of my improvements require little further explanation. When the pinion G is in its ordinary operative position (Fig. 2), the jaw D is securely connected to the rod H, and the sleeve K¹ and arm L are at the right and out of the path of the pin M. When the pinion G is disconnected (Fig. 4), the jaw and rod are disengaged, and the arm L on the sleeve K¹ is shifted into the path of the pin M. The manual adjustment of the disk then results in the rocking of the shaft K and the consequent adjustment of the jaw by the arm J. After this the reconnection of the pinion to its actuating means restores all of the parts to their normal condition.

As previously stated, I have shown my invention only in preferred form and by way of example, and as applied to a particular form of mechanism, but obviously many modifications and alterations therein, and in its mode of adaptation, will suggest themselves to those skilled in the art, without departure from its scope.

Having thus described my invention, its construction and mode of operation, what I claim and desire to secure by Letters Patent of the United States, is as follows:

1. In a typographical casting machine, the combination of a plurality of molds, any selected one of which may be brought into action at will, adjustable line confining devices common to all of said molds, and automatic mechanism to effect the adjustment of said devices to correspond to the selected mold.
2. In a typographical casting machine, the combination of a plurality of molds, means for bringing any selected mold into action at will, adjustable line confining devices common to all of said molds, and mechanism controlled by said means for effecting the adjustment of the confining devices to correspond to the selected mold.
3. In a typographical casting machine, the combination of a plurality of molds, adjustable line confining devices common to

all of said molds, and means for bringing one or another of the molds into action and for simultaneously adjusting the confining devices to correspond therewith.

5 4. In a typographical casting machine, the combination of a mold movable into and out of operative position at will, adjustable line confining devices disconnected from the mold, and automatic mechanism for adjusting said confining devices to correspond to the mold when brought into operative position.

10 5. In a typographical casting machine, the combination of an adjustable mold carrier, adjustable line confining devices mounted independently thereof, and mechanism whereby the adjustment of the mold carrier effects the corresponding adjustment of the confining devices.

15 6. In a typographical casting machine, the combination of an adjustable mold carrier, adjustable line confining devices mounted independently thereof, and means whereby the adjustment of one of said parts effects the corresponding adjustment of the other thereof.

20 7. In a typographical casting machine, the combination of an adjustable mold carrier, means for adjusting it, adjustable line confining devices mounted independently of the carrier, and mechanism controlled by said adjusting means for effecting the corresponding adjustment of the confining devices.

25 8. In a typographical casting machine, the combination of a rotatable mold wheel, adjustable to effect a change of mold, adjustable line confining devices, and automatic mechanism for adjusting said confining devices, said mechanism including means carried by the mold wheel for controlling the extent of its action to correspond to the adjustment of the mold wheel.

30 9. In a typographical casting machine, the combination of a rotatable mold wheel, an adjustable line clamping jaw mounted independently of the mold wheel, a device for adjusting the jaw, and means carried by the mold wheel for operating said device.

35 10. In a typographical casting machine, the combination of a mold carrier adjustable to effect a change of mold, adjustable line confining devices, and mechanism whereby the adjustment of the mold carrier effects the corresponding adjustment of the confining devices, said mechanism being inactive during the normal operation of the carrier.

40 11. In a typographical casting machine, the combination of a mold carrier adjustable to effect a change of mold, means for adjusting the carrier, adjustable line confining devices, mechanism whereby the adjustment of the mold carrier effects the corresponding adjustment of the confining devices, the said mechanism being inactive during the normal operation of the carrier, and connections

whereby the operation of the mold adjusting means renders said mechanism active.

45 12. In a typographical casting machine, the combination of a rotatable mold wheel, an adjustable line clamping jaw, a device 70 for adjusting the jaw, and means carried by the mold wheel for operating said device, said device being movable into and out of engaging relation to said means, for the purpose described.

50 13. In a typographical casting machine, the combination of a rotatable mold wheel, a laterally movable adjusting pinion therefor, an adjustable line clamping jaw, a device for adjusting the jaw, means carried by the 80 mold wheel for operating said device, and connections between the adjusting pinion and said device whereby the lateral movement of the former will effect the movement of the latter into and out of engaging relation to said means, for the purpose described.

55 14. In a typographical casting machine, the combination of a slotted mold movable into and out of operative position at will, adjustable line confining devices disconnected from the mold, and automatic mechanism for adjusting said confining devices to correspond to the mold when brought into operative position, the said mechanism including means to vary the extent of its action to 95 correspond to variations in the length of the mold slot.

60 15. In a typographical casting machine, the combination of a slotted mold movable into and out of operative position at will, 100 adjustable line confining devices, and automatic mechanism for adjusting said confining devices to correspond to the mold when brought into operative position, the said mechanism including means adjustable at 105 will to vary the extent of its action according to a given unit or a fraction of such unit to correspond to variations in the length of the mold slot.

65 16. In a typographical casting machine, 110 the combination of a plurality of molds, any selected one of which may be brought into action at will, adjustable line confining devices common to all of said molds, and automatic mechanism for effecting the adjustment of said confining devices to correspond to the selected mold, said mechanism including means to vary the extent of its action for any given mold.

70 17. In a typographical casting machine, 115 the combination of an adjustable mold carrier, an adjustable line clamping jaw, and automatic mechanism whereby the adjustment of the carrier will effect the corresponding adjustment of the jaw, said mechanism including means adjustable at will to 120 correspond to different sizes of molds.

75 18. In a typographical casting machine, 125 the combination of an adjustable mold carrier, an adjustable line clamping jaw, and 130

automatic mechanism whereby the adjustment of the carrier will effect the corresponding adjustment of the jaw, the said mechanism including means adjustable according to a given unit or a fraction of such unit to correspond to different sizes of molds.

19. In a typographical casting machine, the combination of a rotatable mold wheel, an adjustable line clamping jaw, a device for adjusting the jaw, and means for operating said device, the said means comprising a plate carried by the mold wheel and having a series of holes or perforations, and a member to engage said adjusting device and adapted to be set in one or another of the holes in the plate.

20. In a typographical casting machine, the combination of a rotatable mold wheel, an adjustable line clamping jaw, a device for adjusting the jaw, and means for operating said device, the said means comprising a plate carried by the mold wheel and having a series of holes or perforations, and a member to engage said adjusting device and adapted to be set in one or another of the holes in the plate, the said member being shiftable at will to vary the extent of adjustment of the devices as controlled by its location in the plate.

21. In a typographical casting machine, the combination of a rotatable wheel provided with a plurality of molds, an adjustable line clamping jaw, and means for adjusting the jaw to correspond to one or another of the molds, the said means including a series of abutments carried by the mold wheel, one for each mold, and a device mounted independently of the mold wheel and connected to the jaw, and adapted to be operated by the abutments on the mold wheel.

22. In a typographical casting machine, the combination of a rotatable wheel provided with a plurality of molds, an adjustable line clamping jaw, and means for adjusting the jaw to correspond to one or another of the molds, the said means including a series of abutments carried by the mold wheel, one for each mold, and a device mounted independently of the mold wheel, and connected to the jaw, and adapted to be operated by the abutments on the mold wheel, and the said abutments being capable of rearrangement to correspond to different sizes of molds.

23. In a typographical casting machine, the combination of a plurality of molds, any selected one of which may be brought into action at will, adjustable line confining devices, and automatic mechanism to effect the adjustment of said confining devices to correspond to the selected mold, together with means for locking said confining devices in their different/adjusted positions.

24. In a typographical casting machine,

the combination of an adjustable mold carrier, adjustable line confining devices, mechanism whereby the adjustment of the mold carrier effects the corresponding adjustment of the said confining devices, and means for locking said confining devices in their different adjusted positions.

25. In a typographical casting machine, the combination of an adjustable mold carrier, adjustable line confining devices, mechanism whereby the adjustment of the mold carrier effects the corresponding adjustment of the said confining devices, and means for locking said confining devices in their different adjusted positions, together with automatic means for releasing said locking means when the carrier is adjusted.

26. In a typographical casting machine, the combination of an adjustable mold carrier, an adjustable line clamping jaw, mechanism whereby the adjustment of the mold carrier effects the corresponding adjustment of the jaw, means for locking the jaw in its adjusted position, and automatic devices for rendering said locking means inactive and active before and after the adjustment of the carrier respectively.

27. In a typographical casting machine, the combination of a plurality of molds, means for bringing any selected one into action at will, an adjustable clamping jaw, automatic mechanism for effecting the adjustment of the jaw to correspond to the selected mold, and devices controlled by the operation of the mold selecting means for locking the jaw in its adjusted position.

28. In a typographical casting machine, the combination of a rotatable mold wheel, a laterally movable adjusting pinion therefor, an adjustable line clamping jaw controlled in its adjustment by that of the mold wheel, means for locking the jaw in its adjusted position, and devices operated by the lateral movement of the mold adjusting pinion for rendering said locking means active and inactive alternately.

29. In a typographical casting machine, the combination of an adjustable mold carrier, an adjustable line clamping jaw, means for locking said jaw in its adjusted position, and mechanism whereby the adjustment of the mold carrier effects the release of the locking means.

30. In a typographical casting machine, the combination of an adjustable mold carrier, an adjustable line clamping jaw, means for locking said jaw in its adjusted position, and mechanism whereby the adjustment of the mold carrier effects the release of the locking means, and thereafter the adjustment of the jaw to correspond with that of the mold carrier.

31. In a typographical casting machine, the combination of an adjustable mold carrier, an adjustable line clamping jaw, means

for locking said jaw in its adjusted position, and mechanism whereby the adjustment of the mold carrier effects the disengagement of the locking means and thereafter the adjustment of the jaw to correspond with that of the mold carrier, and finally the reengagement of the locking mechanism to hold the jaw in its new position.

10 32. In a typographical casting machine, the combination of an adjustable mold car-

rier, an adjustable line clamping jaw mounted independently of the carrier, and means to prevent the adjustment of one of said parts without effecting the corresponding adjustment of the other thereof.

In testimony whereof I have affixed my signature in presence of two witnesses.

GEORGE P. KINGSBURY.
